UNITED STATES PATENT OFFICE

GARRETT W. MUDD, OF CHICAGO, ILLINOIS

FILLING MACHINE

Application filed June 27, 1930. Serial No. 464,212.

This invention relates to improvements in machines for filling cans or containers with liquids from a continuous source or supply, and one of the objects of the invention is to provide improved means for delivering one supply into a can or receptacle while another supply is being measured or accumulated for another receptacle, and improved means automatically controlled by the supply of liquid for controlling the discharge of the measured quantities into the respective receptacles.

To the attainment of these ends and the accomplishment of other new and useful objects as will appear, the invention consists in the features of novelty in substantially the construction, combination and arrangement of the several parts hereinafter more fully described and claimed and shown in the accompanying drawings illustrating this invention, and in which

Figure 1 is a view partly in side elevation, partly broken away and partly in section, of a machine of this character constructed in accordance with the principles of this invention.

Figure 2 is a view taken on line 2—2, Figure 1.

Figure 3 is a view similar to Figure 1, on an enlarged scale, with parts broken away and parts in section.

Figure 4 is a view similar to Figure 3, showing the parts in another position.

Figure 5 is a detail sectional view taken on line 5—5, Figure 3.

Referring more particularly to the drawings the numeral 10 designates a suitable supporting structure and 11 a receptacle which is pivotally mounted intermediate its ends as at 12 upon the supporting structure.

Arranged within the receptacle and spaced from the ends thereof is an upright partition 13 which terminates short of the top of the receptacle and disposed adjacent the top of the partition 13 and extending transversely thereacross to project for a short distance beyond each side of the partition 13 is a horizontal partition 14.

The partition 13 divides the receptacle 11 into two compartments, one on each side of

the partition and arranged in each of the compartments is an upwardly inclined partition 15 which extends from the opposite ends 16 of the receptacle 11 at points above the bottom 17 thereof, upwardly and toward the partition 13, each of the partitions 15 terminating short of the partition 13 and being spaced below the transverse partition 14.

The partition 15 divides each of the compartments into a receiving chamber 18 and a discharge chamber 19 and arranged to project into the receptacle 11 is a discharge pipe 20 which is maintained in a fixed position with respect to the pivot 12 of the receptacle 11 and through which pipe 20 the material is supplied to the receptacle.

Arranged in the bottom of each of the chambers 19 and preferably adjacent the respective ends 16 is a discharge outlet 21 and a chute or nozzle 22 is preferably provided adjacent the outlets for directing the material from the outlet.

Each of the outlets 21 is provided with a closure 23 preferably of the slidable type which is arranged to move in guides 24 and is provided with a laterally projecting portion 25 and the closure 23 is normally held in a closing position with respect to the opening 21 preferably by means of a spring 26, one end of which engages the projection 25 and the other end abuts a shoulder 27 carried by the receptacle 11.

The receptacle 11 is adapted to be swung about the pivot 12 so as to position either one or the other of the receiving chambers 18 in a position to receive the material from the pipe 20, according to the direction of movement of the receptacle about its pivot. As one of the discharge outlets 21 is moved into a position to discharge the contents of the chamber 19 into a can or container 28 the other outlet 21 will be moved out of a discharging position, and as the respective outlets move out of discharging position, the respective springs 26 will shift the closures 23 to close said outlet.

As the discharge outlet 21 approaches a discharging position the projection 25 on the respective outlet will engage a stop or member 29 arranged in the path of the projection.

25 and which stop operates to shift the closure 23 against the stress of the spring 26 to uncover the outlet 21.

Any suitable means may be provided for

- 5 rocking the receptacle 11 about its pivot, but a suitable and efficient means embodies a sprocket wheel 30 to which is connected one end of a link 31, the other end of the link being connected as at 32 with the receptacle so 10 that when the sprocket wheel 30 is rotated in the direction indicated by the arrow in Figure 1, the receptacle 11 will be rocked first into the position shown in Figure 1 and later into the position shown in Figure 4.
- 15 The sprocket wheel is adapted to be driven from a motor 33 through the medium of a speed reducer 34 of any suitable or well known construction, and the shaft 35 of which speed reducer is connected by means of a belt 20 with the shaft 37 of the motor.

Connected with the shaft 35 of the speed reducer is a pulley over which another endless belt 38 passes, and this belt in turn passes over a pulley 39 rotatably mounted upon the 25 supporting structure 10. Secured to the shaft 40 of the pulley 39 is a locking member 41 of any suitable construction preferably in the form of a toothed disc and the locking member 41 is given a continuous rotation by 30 the operation of the motor 33.

Loosely mounted upon the shaft 40 is a sprocket wheel 42 over which a sprocket chain 43 passes and which sprocket chain also passes over the sprocket wheel 30.

35 Connected to rotate with the sprocket wheel 42 is a disc 44 and pivotally mounted upon the disc intermediate its ends as at 45 is a locking dog 46 provided with a spring 47 that tends normally to move the dog 46 into 40 engagement with the locking member 41 to lock the disc 44 and the sprocket wheel 42 with the shaft 40 for rotation therewith and thereby impart a rotation to the sprocket wheel 30 from the motor.

45 The operation of the dog 46 is controlled by an electro-responsive device 48, preferably in the form of a solenoid, the armature 49 of which is operatively connected with one end of a lever 50, the latter being pivotally supported intermediate its ends as at 51. One end of the lever 50 is adapted to be moved into the path of rotation of a portion of the dog 46 and a spring 52 tends normally to move the lever 50 into such position so that 50 when the disc 44 is locked for rotation with the shaft 40, and the dog 46 is bodily rotating with the disc, one end of the dog will contact with the end of the lever 50 which is arranged in the path of movement thereof to 55 trip the dog against the stress of the spring 47 and thereby unlock the disc 44 with respect to the shaft 40 to arrest the rotation of the sprocket wheel 30. A retaining pawl 53 may be provided which co-operates with a 60 shoulder 54 on the disc 44 for locking the disc

44 against retrograde movement when the dog 46 is moved into an inoperative or unlocking position with respect to the member 41, a spring 55 being provided to control the retaining pawl 53.

70 The receptacle 11 will thus be rocked about its pivot to alternately discharge the contents thereof into the cans or containers 28, which latter are mounted upon a suitable support 56 and the rocking of the receptacle 11 is 75 automatically controlled by the delivery of the liquid or material to be dispensed into the respective chambers 18.

In the present application of the invention the material to be dispensed is disclosed 80 as a liquid which, when the parts are in the position shown in Figure 3, will fill one of the chambers 19 by being discharged through the space between the transverse partition 14 and the end of the respective inclined partition 15, a vent pipe 57 being provided for 85 each of the chambers 19.

As soon as one of the chambers 19 is filled 90 with the liquid, any additional amount delivered into the receptacle 11 will flow over the partition 14 and into one of the receiving chambers 18 to accumulate therein and the accumulation of the liquid will operate or raise a float 58 connected with a rod 59 that moves in suitable guides 60. One of these 95 floats and an electric circuit make and break device, hereinafter to be described, is associated with each of the chambers 18 and the respective floats will rise and fall according to the quantity of liquid in the chambers 18.

100 These float devices operate to control the electro-responsive device 48 through the medium of contacts 61-62. To the contact 61 is connected a conductor 63 which is also connected to a contact 64. A contact 65 is spaced from the contact 64 and co-operates therewith in a manner to be described, and connected with this contact 65 is a conductor 66 which leads from one side of a suitable source of supply, such as a battery 67. Leading from the other side of the battery is a conductor 68 which is connected to one end of the winding of the electro-responsive device 48.

110 Connected to the other end of the winding of the electro-responsive device is a conductor 69 which is also connected with a contact 70, the latter being disposed in a position that when the float 58 rises the contact 62 will be brought into engagement with the contact 70, thereby completing the circuit through the electro-responsive device 48 and the separated contacts 64-65 in the following manner.

115 Connected for rotation with the pulley 39 is a disc 71 formed of any suitable insulating material such as fiber or the like and carried by the disc is a contact 72 which passes through the disc and is exposed on both sides thereof. This disc 71 operates between 120

the spaced contacts 64—65 and at a predetermined time in the cycle of operation of the machine the disc 71 will be rotated and will assume a position that the contact 72 thereon will be disposed between and in engagement with the spaced contacts 64—65, thereby completing the circuit.

These contacts 64, 65 and 72 constitute a make and break device while the contacts 62 and 70 constitute another make and break device, the latter being influenced by the float 58 and the liquid discharged into the receptacle 11.

It is thought that the operation of the machine will be clearly understood from the foregoing description, but briefly stated it is as follows:

Assuming the parts to be in the position shown in Figures 1 and 3, and liquid is being supplied through the pipe 20, the liquid will accumulate in the compartment 19 which is elevated until the compartment 19 is filled, as shown in Figure 3.

During the filling of this compartment the liquid will be discharged from the compartment 19 which is lowered and any surplus amount of liquid will flow over the partition 14 into the other chamber 18. As the liquid flows out of the chamber 18 which is elevated and into the chamber 19 as shown in Figure 3, the float 58 in that chamber will be lowered, thereby moving the contact 62 away from the contact 70 to break the circuit through the electro-responsive device 48. This will render the electro-responsive device inactive so that the spring 52 will position the end of a portion of the dog 46 to cause the discs 44 and 71 to be locked for rotation with the shaft 40 to shift the receptacle 11 from the position shown in Figure 1 to the position shown in Figure 4.

As soon as the other or filled chamber 18 is raised, the float 58 will be held raised until the liquid flows from the chamber 18 into the chamber 19 sufficiently to cause the float to drop to move the contact 62 away from the contact 70.

It has been found that in operation, a considerable amount of electricity will be consumed in a day's operation of the device if the circuit to the electro-responsive device is not promptly broken after the receptacle is shifted, and it has also been found that the contact 62 will not always promptly move out of engagement with the contact 70. Therefore, in order to conserve the amount of electricity employed and to insure a prompt breaking of the circuit through the electro-responsive device 48 the additional make and break device 64—65—72 is provided.

The circuit for the other chambers 18 and 19 and float 58 is the same as for the float device just described.

In order to remove the receptacles 28 after

they have been filled, a suitable conveyor 73 may be provided.

While the preferred form of the invention has been herein shown and described, it is to be understood that various changes may be made in the details of construction and in the combination and arrangement of the several parts, within the scope of the claims, without departing from the spirit of this invention.

What is claimed as new is:

1. In a filling machine, a shiftably mounted delivery tank provided with two discharge openings one of which is positioned to discharge a portion of the contents of the tank when the other is moved out of discharging position, positively actuated means for shifting the tank, and means responsive to the delivery of a predetermined amount of liquid into the tank for controlling the operation of said shifting means.

2. In a filling machine, a shiftably mounted delivery tank provided with two discharge openings one of which is positioned to discharge a portion of the contents of the tank when the other is moved out of a discharging position, means for shifting the tank, electro-responsive means for controlling said shifting means, means responsive to the delivery of a predetermined amount of liquid into the tank for controlling the said electro-responsive means, closures individual to the discharge openings, means normally operating to close said closures, and means operating to automatically open the closure of the discharge opening which is moved into a discharging position.

3. In a filling machine a pivotally mounted receptacle, means dividing the receptacle into two compartments, a supply pipe having a fixed position, positively actuated means for rocking said receptacle about its pivot to alternately position said compartments to receive a supply from said pipe, discharge outlets individual to said compartments, said outlets being so located with respect to each other that when one is moved into a discharging position the other will be moved out of such position, and means controlled by the delivery of the supply to said compartments for controlling the actuation of the said rocking means for the receptacle.

4. In a filling machine a pivotally mounted receptacle, means dividing the receptacle into two compartments, means for rocking the receptacle about its pivot, a supply pipe having a fixed position, electro-responsive means for controlling the said rocking means, means controlled by the supply of material delivered into one of the compartments while the material is being discharged from the other compartment for controlling the said electro-responsive means to alternately position said compartments to receive a supply from said pipe, and discharge outlets indi-

vidual to said compartments, said outlets being so located with respect to each other that when one is moved into a discharging position the other will be moved out of such position.

5. In a filling machine a pivotally mounted receptacle, means dividing the receptacle into two compartments, a supply pipe having a fixed position, positively actuated means for rocking said receptacle about its pivot to alternately position said compartments to receive a supply from said pipe, means controlled by the supply in said receptacle for controlling the operation of 10 said rocking means, discharge outlets individual to said compartments, said outlets being so located with respect to each other that when one is moved into a discharging position the other will be moved out of such position, closures 15 for the said outlets, and means operating to automatically open said closures when the respective outlets are moved into a discharging position.

6. In a filling machine a pivotally mounted 25 receptacle, means dividing the receptacle into two compartments, a supply pipe having a fixed position, means for rocking said receptacle about its pivot to alternately position the compartments to receive a supply from said pipe, electro-responsive means for 30 controlling the second recited means, means controlled by the supply of material delivered into the respective compartments for controlling the action of said electro-responsive 35 means, and discharge outlets individual to said compartments, said outlets being so located with respect to each other that when one is moved into a discharging position the other will be moved out of such a position.

7. In a filling machine a pivotally mounted receptacle, means dividing the receptacle into two compartments, a supply pipe having a fixed position, means for rocking said receptacle about its pivot to alternately position the compartments to receive a supply from said pipe, electro-responsive means for 45 controlling the second recited means, means controlled by the supply of material delivered into the respective compartments for controlling the action of said electro-responsive means, and discharge outlets individual to said compartments, said outlets being so located with respect to each other that when one is moved into a discharging position the other will be moved out of such a position, the said means which controls the electro-responsive means embodying a float in each of the compartments and a circuit make and break device individual to the floats and responsive in operation to the rising and falling 55 movements of the respective floats.

8. In a filling machine a pivotally mounted receptacle, means dividing the receptacle into two compartments, a supply pipe having a fixed position, means for rocking said re-

ceptacle about its pivot to alternately position the compartments to receive a supply from said pipe, electro-responsive means for controlling the second recited means, means controlled by the supply of material delivered 70 into the respective compartments for controlling the action of said electro-responsive means, discharge outlets individual to said compartments, said outlets being so located with respect to each other that when one is moved into a discharging position the other will be moved out of such a position, closures 75 individual to said discharge outlets, and means for automatically opening said closures, as the respective discharge openings are 80 moved into discharging position.

9. In a filling machine a pivotally mounted receptacle, means dividing the receptacle into two compartments, a supply pipe having a fixed position, means for rocking said receptacle about its pivot to alternately position the compartments to receive a supply from said pipe, electro-responsive means for controlling the rocking means, means controlled by the supply of material delivered 90 into the respective compartments for controlling the action of said electro-responsive means, a make and break device for rendering the electro-responsive device inactive after the latter has been rendered active, and discharge outlets individual to said compartments, said outlets being so located with respect to each other that when one is moved into a discharging position the other will be moved out of such a position.

10. In a filling machine a pivotally mounted receptacle, means dividing the receptacle into two compartments, discharge outlets individual to the compartments, positive means for rocking the receptacle about its pivot to alternately position the compartments to receive a supply from said pipe, discharge outlets individual to the compartments and so arranged with respect to each other that when one is moved into a discharging position the other will be moved out of such a position, an electro-responsive device, a circuit in which said electro-responsive device is included, means individual to the compartments and controlled in operation by the supply of material delivered to the respective compartments for controlling said circuit, the said rocking means embodying a continuously rotating locking member and a locking pawl co-operating therewith, and means responsive to the action of said electro-responsive means and adapted to be positioned in the path of movement of a portion of said pawl to render the latter inactive with respect to its co-operating locking member.

11. In a filling machine, a pivotally mounted receptacle, a partition dividing the receptacle into two sections, an additional partition in each of said sections and co-operating with the first said partition to divide the

section into a receiving and a delivery compartment having communication with each other, a discharge outlet for each of said delivery compartments, the last said partition being so arranged that when the material is being delivered into the receiving compartment, material will be discharging from one of the delivery compartments, fixed means for delivering material into the receiving compartments, and means for 10 rocking the receptacle upon its pivot to alternately place the said receiving compartments to receive material from said fixed means.

12. In a filling machine, a pivotally mounted receptacle, a partition dividing the receptacle into two sections, an additional partition in each of said sections and co-operating with the first said partition to divide the section into a receiving and a delivery compartment having communication with each other, a discharge outlet for each of said delivery compartments, the last said partition being so arranged that when the material is being delivered into the receiving compartment, material will be discharging from one of the delivery compartments, fixed means for delivering material into the receiving compartments, and means controlled by the supply of material which is being delivered into the receiving compartment that is positioned to receive such supply from the said delivery means for rocking the receptacle upon its pivot to alternately place the said receiving compartments to receive material from said fixed means.

13. In a filling machine, a pivotally mounted receptacle, a partition dividing the receptacle into two sections, an additional partition in each of said sections and co-operating with the first said partition to divide the section into a receiving and a delivery compartment having communication with each other, a discharge outlet for each of said delivery compartments, the last said partition being so arranged that when the material is being delivered into the receiving compartment, material will be discharging from one of the delivery compartments, fixed means for delivering material into the receiving compartments, means for rocking the receptacle upon its pivot to alternately position the said receiving compartments to receive material from the said fixed means, electro-responsive means for controlling the operation of said rocking means, and means controlled by the supply of material to either of said receiving compartments for controlling said electro-responsive means.

14. In a filling machine a pivotally mounted receptacle, means dividing the same into two compartments each having a discharge outlet, a fixed source of supply of material for the receptacle, means for rocking the receptacle on its pivot to alternately position

the compartments with respect to the said source of supply to receive material therefrom, means for controlling said rocking means and embodying an electric circuit, an electro-responsive device included in said circuit, means controlled by the material being delivered into one of said compartments for controlling said electro-responsive device, and additional means rendered active by the actuation of said electro-responsive device for rendering the said circuit inactive to arrest the operation of the said rocking means.

15. In a filling machine, a pivotally mounted receptacle, a partition dividing the receptacle into two sections, an additional partition in each of said sections and co-operating with the first said partition to divide the section into a receiving and a delivery compartment having communication with each other, a discharge outlet for each of said delivery compartments, the last said partition being so arranged that when the material is being delivered into the receiving compartment, material will be discharging from one of the delivery compartments, fixed means for delivering material into the receiving compartments, electrical controlled means for rocking the receptacle upon its pivot to alternately position the said receiving compartments to receive material from said fixed means, a circuit in which the said electrically controlled means is included, floats individual to said receiving compartments, and make and break means individual to the floats for controlling said circuit.

16. For use in a filling machine of the character described a pivotally mounted receptacle, an upright partition dividing said receptacle into two sections, a partition extending transversely across said upright portion and beyond the sides thereof and spaced above the bottom of said receptacle, upwardly inclined partitions on opposite sides of said upright partition extending from the opposite end of the receptacle from points above the bottom thereof towards and terminating short of the upright partition and beneath and spaced below the said transverse partition, and discharge outlets leading from the bottom of said receptacle beneath each of said upwardly inclined partitions.

17. In a filling machine of the character described a pivotally mounted receptacle, an upright partition dividing said receptacle into two sections, a partition extending transversely across said upright portion and beyond the sides thereof and spaced above the bottom of said receptacle, upwardly inclined partitions on opposite sides of said upright partition extending from the opposite end of the receptacle from points above the bottom thereof towards and terminating short of the upright partition and beneath and spaced below the said transverse partition,

discharge outlets leading from the bottom of said receptacle beneath each of said upwardly inclined partitions, a fixed inlet pipe extending into the receptacle, means for rocking the receptacle upon its pivot to alternately position the space between the said upright partition and said inclined partitions on opposite sides of the former with respect to said pipe, and means controlled by the supply of material on either side of the said upright partition for controlling the rocking of said receptacle.

18. In a filling machine of the character described a pivotally mounted receptacle, an upright partition dividing said receptacle into two sections, a partition extending transversely across said upright portion and beyond the sides thereof and spaced above the bottom of said receptacle, upwardly inclined partitions on opposite sides of said upright partition extending from the opposite end of the receptacle from points above the bottom thereof towards and terminating short of the upright partition and beneath and spaced below the said transverse partition, discharge outlets leading from the bottom of said receptacle beneath each of said upwardly inclined partitions, a fixed inlet pipe extending into the receptacle, means for rocking the receptacle upon its pivot to alternately position the space between the said upright partition and said inclined partitions on opposite sides of the former with respect to said pipe, and means controlled by the supply of material on either side of the said upright partition for controlling the rocking of said receptacle, the last said means embodying floats and electric circuit make and break devices controlled by the said floats.

40 19. In a filling machine of the character described a pivotally mounted receptacle, an upright partition dividing said receptacle into two sections, a partition extending transversely across said upright portion and beyond the sides thereof and spaced above the bottom of said receptacle, upwardly inclined partitions on opposite sides of said upright partition extending from the opposite end of the receptacle from points above the bottom thereof towards and terminating short of the upright partition and beneath and spaced below the said transverse partition, discharge outlets leading from the bottom of said receptacle beneath each of said upwardly inclined partitions, a fixed inlet pipe extending into the receptacle, means for rocking the receptacle upon its pivot to alternately position the space between the said upright partition and said inclined partitions on opposite sides of the former with respect to said pipe, means controlled by the supply of material on either side of the said upright partition for controlling the rocking of said receptacle, the last said means embodying floats and electric circuit make and break devices

controlled by the said floats, and an additional electric circuit make and break device automatically rendered active for controlling said rocking means.

In testimony whereof I have signed my name to this specification, on this 5th day of June, A. D. 1930.

GARRETT W. MUDD.
